EAR PROTECTOR

Benjamin O. Fanslow, Rockville Centre, N. Y.

Application March 25, 1947, Serial No. 736,931

6. Claims.

Application March 2
6 Claims.

1

This invention is concerned with an ear protector or ear muff having a structure for covering the external ear.

One of the features of the invention is the provision of an ear protector having a muff structure and a clamp structure, wherewith the muff structure can be quickly and easily applied to or removed from the ear, and the clamp structure can be easily actuated for attachment to or release from the ear.

Another feature of the invention is the provision of a clamp structure for an ear protector, which includes a body of resilient material providing pivot mounting and spring portions for engagement with a movable piece which, in one position, serves to hold the assembly to the ear and, in another position, permits engagement with or disengagement from the ear.

A further feature of the invention is the provision of a clamp structure of two parts, including cooperating elements which prevent the accidental opening of the clamp when applied to the ear, and the accidental closing of the clamp when positioned ready for engagement with the ear.

With these and other features as objects in view, as will appear in the course of the following description and claims, illustrative forms of practice of the invention are shown on the accompanying drawings in which:

Figures 1 and 2 are, respectively, elevations of the ear protector from the outer and the inner side;

Figure 3 is an upright sectional view substantially on broken line 3-3 of Figure 2;

Figure 4 is an exploded view, showing the two parts of a first form of clamp structure;

Figures 5 and 6 are enlarged views, showing the clamp structure in section, in its clamping and releasing positions;

Figure 7 is an exploded view of another form of practice:

Figure 8 is a view of this other form, in section and showing the parts in opened position; and

Figure 9 is a section substantially on line 9—9 of Figure 5, showing the engagement with the ear lobe in each illustrated form of the device, the cloth coverings being omitted for simplicity.

The ear protector comprises a muff structure and a clamp structure. In Figures 1-3, the muff structure is provided by an outer piece 10 and an inner piece 11, which may be joined at their abutting edges by stitching 12 (Figure 3). It is preferred to form the external or outer surface of a wind-impermeable flexible fabric such as

leather or closely woven material, while the inner face is provided by fleecing 13. It will be noted that these parts may be joined together with the fleecing at the outside, and then turned inside out to provide a reversed seam at the stitching 12. The parts 10, 11 are designed and arranged to fit over the external ear, and also to fit between the external ear and the head of the wearer. Within the muff structure, in its position for use, a tab 15 is secured to the inner piece 11 (Figures 3 and 5) to form a pocket with a downwardly directed opening.

In the form of structure shown in Figures 4-6, a clamp body 20 is formed as a unit of resilient material, and has a web 21 and the two walls 22 extending from this web and formed with apertured lugs 23 near the lower end of the body. Slits 24 extend along the web, close to the walls 22, and provide a spring blade 25 between the lower ends of these walls. The lower or free end of the spring blade 25 is reduced in thickness to form a shoulder 26 spaced from this free edge. It is preferred to have openings 28 in the body, through which stitches may be passed for securing this body within the pocket provided by tab 15.

A movable clamp part has the general form of a crank lever with the up-standing tongue 30, the aperture 31 for a pivot pin, and the finger 32 which extends toward the blade spring 25. A pivot pin 35 extends through the lugs 23 and the aperture 31 for the permissive swinging movement of the movable part. It is preferred to provide a soft covering 36 about the tongue 30, to cushion the engagement with the ear; for this purpose, the tongue 30 may have an aperture 38 through which a securing stitch may be passed.

By construction and arrangement, the shoulder 26 of the spring blade 25 overlies the finger 32 when the clamp structure is engaged with the ear lobe, so that outward or clockwise rocking movement of the tongue 30 is opposed by the resilience of this spring blade. When the finger 32, however, is forced upwardly by pressure applied adjacent its free edge, it presses the spring blade 25 outwardly and its tongue 30 is moved clockwise into the position of Figure 6, until the free edge of the finger 32 comes above the shoulder 26, as shown in Figure 6. When the parts are in the position of Figure 5, the shoulder prevents a greater clockwise movement of the tongue 30, and the spring blade 25 exerts pressure against the finger 32 in the direction of pivot 35.

When the parts 10, 11 of the muff have been
55 sewn and inverted, the clamp structure can then

be introduced into the muff, by sliding the body upwardly into the pocket provided by the tab 15, and securing it in place by threads passed through the holes 28. The lower ends of the pieces 10, 11 can then be overlapped and sewed together to close the bottom of the muff structure and hold the clamp structure in position.

The device can be applied to the ear by pressing relatively upwardly (Figure 5) upon the finger 32, to make sure that the tongue 30 is in the position of Figure 6, i. e., that it is in opened position. The protector is then placed upon the ear, by slipping it on from the rear and top, with the part 11 lying between the ear and the wearer's head. The lower portion is then slipped around the lower lobe of the ear, so that this lobe comes between the tab 15 and the protective covering 36 on the movable tongue 30. Pressure is then exerted against the piece 10, from the exterior, so that the tongue 30 is moved inwardly or counterclockwise from the position of Figure 6, until the finger 32 passes the shoulder 26 and the spring blade 25 can now act to hold the lower lobe of the ear lightly clamped between the body part and the movable part (Figure 9).

The device can be released and removed by pressing upwardly against the lower part of the movable structure, wherewith the finger 32 is caused to move clockwise about the pivot 35 and pass from the position of Figure 5 into that of Figure 6. The clamp is thus opened, and the structure can be stripped from the ear.

In the modified form shown in Figures 7 and 8, the body 20 is essentially the same as before, with the walls 22, apertured lugs 23, slits 24, spring tongue 25, and the shoulder 26.

The movable part has the upwardly-extending clamp tongue 30, the aperture 31 for the pivot pin, and the engaging finger 32. In this modified form, an actuator piece is also provided, consisting of the actuator finger 40 and the apertured lugs 41 which are mounted on the same pivot 35 that provides for the swinging movement of movable part 30, 32. By construction and arrangement, the actuator finger 40 extends a greater distance from the axis than the finger 32 of the movable part.

The method of applying and removing an ear protector having this modified form of clamp structure is essentially the same as before. With this modified arrangement, upward pressure against the actuator finger 40 causes the movable tongue 30 to move away from the body 20. In this form, continued movement of the actuator finger 40 causes greater distortion of the spring blade 25, until the finger 32 is cleared by the shoulder 26 and tongue 30 may thus open to receive the ear lobe. The actuator finger 40 finally comes against the shoulder 26, wherewith pressure is exerted by the spring blade so that the actuator structure is thus held against return movement. When the tongue 30 is pressed inwardly, however, the corresponding lower finger 32 engages the actuator finger 40, and presses this in a counterclockwise direction until it is below the free edge of the spring blade 25, whereupon this spring then serves to maintain the tongue 30 under light clamping pressure upon the ear lobe.

It is preferred to form the parts 10, 11, 15, 36 of flexible material such as leather or fabric, and they can be made and assembled in various sizes. It is presently preferred to form the spring blade 25 integral with the body structure, by having this body structure made of resilient material. It has been found that plastics, such as vinyl resins,

and acrylic resins, are commercially obtainable in sheet form and of sufficient resiliency for the purposes intended. Such sheets can be cut, drilled, and hot-formed to provide the structures as shown. Phenolic and urea resins of thermosetting type can be employed by hot-holding. Such resins are presently preferred, as they are not affected by cold, nor by water, and have a low heat conductivity and low specific content so that they neither serve to abstract heat from the wearer's ear, nor to conduct such heat to the exterior of the device. Obviously, metal can be used, with preference for non-corrosive alloys.

15 In each form, as shown by Figure 9, the flexible ear lobe L is engaged by the tongue 30, under the resilient pressure exerted therethrough from the spring blade 25, and a part of the lobe is pressed into the channel between the walls 22. Thus, relative sliding movement, in the directions of the double-headed arrow in Figure 9, between the clamping structure and the ear lobe is prevented. The assembly is hence held upon the ear against accidental displacement by contact with 20 the hand, etc., by use of a lesser pressure or clamping force than would be required for such assurance if the body 20 and the tongue 30 had flat opposing surfaces; and therewith the illustrated device is free of necessity of employing such pressures as might restrict circulation in the ear lobe, or activate nerve termini, with resultant discomfort.

30 It is obvious that the invention is not limited with the specific forms shown, but that it may be employed in many ways within the scope of the appended claims.

I claim:

1. An ear protector comprising a muff structure fitting over the external parts of the ear and between the ear and head, and a two-part clamp structure secured to the muff structure and effective for engaging the lower lobe of the ear; said clamp structure comprising a part with spaced parallel walls and a second intermediate 40 part movable with respect to the first part and receivable between the walls thereof, said parts being constructed and arranged in the muff structure to lie one outside and one inside the lower ear lobe when the protector is positioned on the ear, and a spring on one said part and a spring-cooperative portion on the other part for detaining the movable part in either end moved position relative to said body part.

2. An ear protector comprising a muff structure fitting over the external parts of the ear and between the ear and head, said muff structure having a downwardly open pocket at its lower end, and a clamp structure comprising a body part located and held in said pocket, and a movable part pivoted to said body part and located within the muff structure and outside the pocket, said body part having an integral leaf spring, said movable part having a finger engageable by said spring whereby the movable part is held by said spring against ear-disengaging swinging movement away from the body part.

3. A clamp structure for an ear protector comprising a body of resilient material and having a web and walls extending from the web, the body having slits along the web whereby to provide a blade spring, a movable part having an ear-engaging tongue cooperative with the body for clamping to the ear, pivot means connecting the movable part to the body, and a finger on the movable part for engaging said spring and

cooperative therewith to maintain the body and movable part in ear-engaging position.

4. A clamp structure for an ear protector comprising a body having a web and walls extending from the web, a movable part having an ear-engaging tongue cooperative with the body for clamping to the ear, pivot means connecting the movable part to said walls, said body having a blade spring as a part thereof, said blade spring having its free end downward and having a shoulder spaced from said free end, said movable part having a finger engageable with said blade spring whereby said blade spring can maintain the movable part in ear-engaging position, the pivot means, the shoulder, and the finger being so constructed and arranged that when the finger engages the shoulder the blade spring is effective to hold the tongue in disengaged position.

5. A clamp structure for an ear protector comprising a body of resilient material and having a web and walls extending from said web, said body being slit along a part of said web whereby said web part provides a blade spring, said spring having a shoulder spaced from the free end thereof, a movable part pivotally secured between the body walls opposite the free end of the spring and having an earlobe-engaging tongue cooperative with the body, said movable part having a finger extending toward said spring and engageable thereby to prevent swinging movement of the movable part out of earlobe engaging position, said finger and spring shoulder being so constructed and arranged that when the finger lies against the shoulder the spring prevents inward ear-engaging movement of the tongue and the shoulder limits outward movement of the tongue.

6. A clamp structure for an ear protector comprising a body of resilient material and having

a web and walls extending from said web, said body being slit along a part of said web whereby said web part provides a blade spring, said spring having a shoulder spaced from the free end thereof, said walls including apertured lugs, a movable part located between the body walls opposite the free end of the spring and having an earlobe-engaging tongue cooperative with the body, a pivot pin extending through said lugs and movable part, said movable part having a finger extending toward said spring and engageable thereby to prevent swinging movement of the movable part out of earlobe engaging position, said finger and spring shoulder being so constructed and arranged that when the finger lies against the shoulder the spring prevents inward ear-engaging movement of the tongue and the shoulder limits outward movement of the tongue, and an actuator part mounted on said pivot pin for engaging and moving said finger to cause the movable part to pass toward earlobe-disengaging position, said actuator being constructed and arranged whereby upon movement thereof it displaces the spring from the finger and permits the finger to pass the shoulder.
